UNITED STATES PATENT OFFICE

ELIJAH C. GREISEN, OF WAUWATOSA, WISCONSIN, ASSIGNOR TO ALLES-CHALMERS MANUFACTURING COMPANY, OF MILWAUKEE, WISCONSIN, A CORPORATION OF DELAWARE

DRYING CYLINDER

Application filed October 22, 1930. Serial No. 490,411.

This invention relates to improvements in drying cylinders of the type in which the drying medium, such as heated air, is admitted into longitudinally extending internal draft chambers and discharged therefrom into the interior of the cylinder through a longitudinal series of openings associated with each of the draft chambers. A drying cylinder of this type has been disclosed, for instance, in the patent to Cummer, 888,475, May 26, 1908.

It is an object of the invention to provide a drying cylinder which is simple and compact in construction and efficient in operation.

A more particular object of the invention is to provide a drying cylinder of this general character which can be manufactured with a minimum of expense for material as well as labor.

In order to most advantageously attain the objects of the present invention, the drying cylinder may be provided with internal sheet metal members cooperating with each other and the cylinder wall to form the draft chambers, and preferably one of the sheet metal members has an extended portion shaped to form a lifting or cascading blade projecting from the draft chamber into the cylinder. The work which is necessary to assemble the cooperating sheet metal members can be done outside of the cylinder so that fitting work within the cylinder is practically eliminated, it being only necessary to fasten the assembled sheet metal members to the inside of the cylinder. The sheet metal member which forms the trailing wall of the draft chamber is provided with a longitudinal series of gas discharge openings, and means are provided to prevent the material within the cylinder from working out through these openings while the cylinder is being rotated. These means are designed, according to the invention, in such a manner that they can be assembled with the draft chamber walls outside of the cylinder and do not require any fitting work within the cylinder.

These and other objects and advantages of the invention will be apparent from the fol-

lowing description. A clear conception of an embodiment of the invention and of the operation of a device constructed in accordance therewith, may be had by referring to the drawing accompanying and forming a part of this specification, in which like reference characters designate the same or similar parts in the several views.

Fig. 1 is a longitudinal sectional elevation of a drying apparatus embodying the improved cylinder in working relation.

Fig. 2 is a cross-section of the cylinder alone.

Fig. 3 is a perspective view showing part of the cylinder wall and draft chambers associated therewith.

Figs. 4 and 5 are detail views showing a hood for the discharge openings of the draft chambers.

The numeral 1 designates the drying cylinder as an entirety, which consists of an outer sheet metal shell 2 and a plurality of internal draft chambers, in this instance ten, which extend along the cylinder wall substantially from one end to the other. Each draft chamber is confined by the cylinder wall 2 and two sheet metal members 3 and 4, secured to the inner surface of the cylinder in circumferentially spaced relation. The direction in which the cylinder rotates, when in operation, is indicated by the arrows in Figs. 2 and 3, and it will be understood that the wall formed by the member 3 is a trailing wall while the wall formed by the member 4 will be referred to as a leading wall. The member 4 has a portion bent to an angle of inclination so as to intersect the plane of the trailing wall, and the member 3 is fastened at its inner end to said inclined portion of the member 4, preferably by welding. An inner portion of the member 4 is shaped to form a lifting or cascading blade, the end thereof being preferably straight and disposed as shown, so as to retain the material to be dried in a trough while it is lifted within the cylinder.

The drying medium is admitted to each of the draft chambers through a longitudinal series of circular inlet openings 5 associated with the cylinder wall 2, and a longitudinal series of rectangular outlet openings 6 is pro-

vided in the trailing wall of each chamber. The inlet openings of the cylinder wall and the outlet openings of the trailing wall are preferably disposed in staggered relation in order to reduce the chance that material within the cylinder works out through these holes. Moreover, hoods 7 are placed over each of the outlet openings of the trailing wall. Each hood has internal guard ribs 8 and 9 adjacent to the respective outlet opening 6, and external lugs 10 having bolt holes registering with corresponding holes in the trailing wall. Mounting bolts 11 inserted into these holes serve to hold the hoods secured to the trailing wall. The sheet metal members 3 and 4 are secured with their outer ends to the cylinder wall 2 in any suitable manner, preferably by welding, flanges 12 and 13 projecting laterally from the members 3 and 4, respectively, being provided for this purpose.

In operation, products of combustion and heated air are drawn from the furnace 14, shown in Fig. 1, into the cylinder by a suction fan or the like connected to the interior thereof by a pipe line 15 and a cylinder end fitting 16. From the upper furnace chamber which encloses the drying cylinder the gases are first admitted to the draft chambers within the cylinder through the holes 5 in the cylinder wall, and from there they pass into the interior of the cylinder through the discharge openings 6 in the trailing walls of the draft chambers. While the gases circulate in the described manner the cylinder is rotated in the direction indicated in Figs. 2 and 3, by a suitable mechanism indicated by 17 in Fig. 1. It will be seen from Fig. 2 that the material accumulating in front of the leading walls at the bottom of the cylinder will be retained during the rotation of the cylinder within the troughs formed by the inner ends of the sheet metal members 4 until it reaches a relatively high elevation within the cylinder, whereby the cascading and drying process is rendered highly efficient. It will further be seen that the sheet metal members within the cylinder not only provide efficient cascading blades but also draft chambers which serve the additional purpose of increasing the longitudinal stability of the cylinder.

The sheet metal members 3 and 4 as well as the hoods 7 may be assembled outside of the cylinder and then fastened as a unit to the cylinder wall whereby any difficult fitting work within the cylinder is avoided.

The preferred embodiment of the invention herein described is capable of certain modifications without departure from the scope of the invention defined in the following claims.

It is claimed and desired to secure by Letters Patent:

1. A drying cylinder comprising a rotary continuous annular shell, box section members forming longitudinally extending inter-

nal draft chambers associated with said shell and having gas discharge openings in their trailing walls, and means associated with each of said discharge openings to prevent the material within the cylinder from working out therethrough, said means comprising a shield member fastened to said trailing wall and extending from an inward portion thereof towards said shell, and guard elements extending rearwardly from said trailing wall and disposed to direct the flow of gas from the respective discharge opening underneath said shield member.

2. A drying cylinder comprising a rotary continuous circular shell, box section members forming longitudinally extending internal draft chambers associated with said shell and having gas discharge openings in their trailing walls, and means associated with each of said discharge openings to prevent the material within the cylinder from working out therethrough, said means comprising a hooded member having an outer wall extending from an inward portion of said trailing wall towards said shell, side walls adjacent to the respective discharge opening, and internal ribs projecting rearwardly from said trailing wall and extending between said side walls.

In testimony whereof, the signature of the inventor is affixed hereto.

ELIJAH C. GREISEN.
